UNITED STATES PATENT OFFICE.

SAMUEL BORLAND, OF WELLSTON, OHIO.

SIGNAL APPARATUS.

1,108,860.

Specification of Letters Patent. Patented Aug. 25, 1914.

Application filed September 30, 1912. Serial No. 723,044.

To all whom it may concern:

Be it known that I, SAMUEL BORLAND, a citizen of the United States, residing at Wellston, in the county of Jackson and State of Ohio, have invented certain new and useful Improvements in Signal Apparatus, of which the following is a specification.

My invention relates to railway signal apparatus and particularly to a signal lantern embodying carriers for one or more fusees or flare torches, a container for torpedoes or detonators and a receptacle for matches.

It is the practice in railway operations, when a train is stopped at a point other than a regular station stop, to protect the train by sending a flagman or signal man a considerable distance over the track to the rear of the train whose business it is to stop any train which may be following. To enable the signal man to signal an approaching train he is provided with a lantern and in addition thereto with one or more fusees or flare torches and also with torpedoes or detonators adapted to be secured to the track to provide an auditory signal in the event that the visual signals are overlooked. It is customary to carry the lantern, the fusees and torpedoes separately, the latter being usually carried in the signal man's pocket. In the excitement of leaving the train, particularly in the event of a wreck, one or more of these form of signal devices may be overlooked or forgotten. The fusees as usually constructed are provided with a friction head whereby they may be ignited by rubbing on a friction surface to be found upon the cap or cover normally inclosing the friction head. It sometimes happens, however, particularly if the fusee has become damp that it will not ignite by frictional contact with the cap but it is necessary that it be lighted with a match. Likewise in stormy weather the signal man's lantern is likely to be accidentally extinguished. If in such emergency, he finds himself without a supply of matches or that his match supply carried in his pocket is wet and therefore useless he may be unable to use his signal devices to prevent collision.

The object of the present invention is to provide a suitable carrier for the several portions of signal devices which will be simple and cheap in construction in which the several forms of devices, together with a supply of matches may be stored whereby none

of the forms of signal devices will be readily overlooked or lost and in which each one will be readily and quickly accessible and which will be unlikely to get out of repair.

With the above primary and other incidental objects in view as will more fully appear in the specification, the invention consists of the features of construction, the parts and combinations thereof and the mode of operation or their equivalents as hereinafter described and set forth in the claims.

Referring to the drawings, Figure 1 is a perspective view of the assembled apparatus forming the subject matter hereof. Fig. 2 is a detail vertical sectional view of the base of the device disclosing the receptacle for the torpedoes or detonators. Fig. 3 is a detail sectional plan view of the base of the device. Fig. 4 is a detail plan view of one of the fusee clasps.

Like parts are indicated by similar characters of reference throughout the several views.

In the drawings, 1 is a lantern of ordinary construction and of the type usually employed in railway operations. As is usual in this type of lantern the glass globe 2 is surrounded with a protective wire cage 3.

The fusees or flare torches comprise cylindrical bodies or shafts 4 terminating at one end in a spike 5 and provided at their opposite extremity with a closing cap or cover 6. These fusees are arranged in upright spaced relation about the exterior of the cage 3. Clasps or loops 7 are provided upon the cage 3 and adapted to encircle the shaft 4 of the fusees to maintain it in position, while the spike 5 thereof engages a suitable socket 8 projecting upward from the base of the lantern. The clasps 7 are substantially U shaped in form and may be attached to the cage 3 at both extremities. They are, however, preferably formed from resilient or spring material and attached only at one extremity leaving their other extremity free whereby the clasps may be flexed outward to accommodate fusees of greater diameter.

The socket 8 may be of any desired form to receive the spike 5 but preferably comprises a plate of sheet metal secured in upright position to the base of the lantern and having a perforated head bent inward to a position substantially at right angles to the general plane of the plate. The spikes 5 of

the fuses are adapted to project through the perforated heads of the socket members 8 upon the inner side of the plate portion of the socket whereby the sharpened points of the spikes will be protected against injury and by which they will be protected against entanglement in the clothing of the signal man or other fabrics or objects in their vicinity. By the engagement of the 10 spikes 5 in the socket 8 and the engagement of the clasp 7 about the shaft of the fuses the fuses are securely held in place while at the same time they may be readily disengaged by withdrawing them upward 15 through the clasps or loops 7.

To provide for carrying the torpedoes or detonators there is provided about the base or pedestal of the lantern an annular container 9 of truncated conical form. This 20 container 9 is cut away for a limited space as is indicated between the point 10-10 in Fig. 3 to permit access to the interior thereof for the insertion and removal of the torpedoes. The container 9 is revolvably 25 mounted upon the base or pedestal of the lantern whereby it will be permitted a limited oscillatory movement. The oscillatory movement of the receptacle 9 is limited by the engagement of a spring catch 11 with one of the brace wires 12 of the lantern 30 frame at the limit of its stroke in either direction.

There is carried upon the base portion of the lantern a fixed shield or cover plate 13 35 which normally covers the opening 10-10 of the receptacle 9. The spring catch 11 is adapted to engage one of the brace wires 12 as shown in Fig. 1 to lock the oscillatory receptacle 9 in its adjusted or closed position 40 with the opening 10-10 in registry with the shield or cover plate 13. By releasing the catch 11 from the base wire 12 the torpedo receptacle may be rotated to bring the opening 10-10 beneath the shield 45 or cover plate 13.

Located within the oscillatory receptacle or container 9 is a revoluble carrier 14 provided with a plurality of partitions 15 dividing the carrier into a series of compartments, each adapted to contain a single torpedo. The carrier 14 is capable of rotary movement within the container 9 whereby each of the compartments formed by the partition 15 may be brought in succession 50 into registry with the opening 10-10 of the container 9. By first oscillating the container 9 to shift its open section 10-10 from beneath the shield or cover plate 13 and thereafter rotating the carrier 14 within the 55 container the torpedo or detonator may be removed from any one of the compartments in the carrier.

Located at one side of the lantern body occupying an inclined position above the receptacle 9 is a tubular receptacle 16 having

a removable cap or cover 17 adapted to contain a supply of matches.

The fuses being arranged in spaced relation about the cage of the lantern do not interfere with the projection of light in any 70 direction as there is always sufficient space between adjacent fuses. The torpedoes or detonators being located within the container or receptacle 9 below the level of the flame of the lantern and each located in a 75 separate compartment are protected against dampness and may be safely carried without danger of accidental explosion. When carried in the pockets of signal men as is the usual custom there is always grave danger 80 of an accidental explosion, through the accidental striking of the signal man's pocket in climbing on or off the train or through any shock or jolt, which would result in serious injury to the signal man.

By the use of the carrier herein described not only is all danger to the operator obviated but also the danger of the operator overlooking or forgetting any one of the forms of signal devices which are contained 90 in the carrier in position wherein they will be safe from loss or injury while at all times readily accessible, and wherein they will not interfere with the usual use of the lantern.

From the above description it will be apparent that there is thus produced a device of the character described possessing the particular features of advantage before enumerated as desirable but which obviously is susceptible of modification in its form, proportion, detail construction and arrangement of parts without departing from the principle involved or sacrificing any of its advantages.

While in order to comply with the statute, the invention has been herein described in language more or less specific as to certain structural features, it is to be understood that the invention is not limited to any 100 specific details but that the means and mechanism herein shown and described comprise but one mode of putting the invention into effect and the invention is therefore claimed broadly in any of its possible 105 forms or modifications within the scope of the appended claims.

Having thus described my invention, I claim;

1. In a lantern, an annular rotatable 120 chamber surrounding the pedestal of the lantern and having an access opening therein, a rotatable tray located within the chamber and concentric therewith, and a fixed closure shield for the access opening 125 with which the rotatable chamber cooperates.

2. In a lantern, an annular chamber surrounding the pedestal of the lantern and having an access opening therein, a rotatable 130

- tray contained within the annular chamber adapted by its rotation to present successive portions of the tray at the access opening and a closure shield for said opening.
3. In a lantern, an annular rotatable chamber concentric with the base plate of the lantern, and having an access opening therein, a tray located within the chamber and concentric therewith, and a fixed shield with which the rotatable chamber co-operates to close the access opening.
4. In a lantern, an annular chamber surrounding the pedestal of the lantern, and having an access opening therein, a tray concentrically located within the chamber, said chamber and tray being relatively rotatable in relation one with the other to present successive portions of the tray at the access opening.
5. In a lantern, an annular chamber surrounding the pedestal of the lantern and having an access opening, a tray concentrically located within the chamber, and a closure shield for the access opening, the chamber and shield being concentrically adjustable in relation one with the other.
6. In a lantern, an annular chamber surrounding the pedestal of the lantern and having an access opening therein and a shield for said access opening, the chamber and shield being relatively adjustable concentrically in relation one with the other.
7. In a lantern as described, a chamber concentric with the base thereof and provided with an access opening, an independently revolute tray located within the
- chamber adapted by its rotation to successively present successive portions of the tray at the access opening of the chamber and a closure shield co-operating with the chamber to close the access opening.
8. In a lantern as described, an annular chamber concentric with the base of the lantern, and having an access opening therein, an independently rotatable tray contained within the chamber and adapted by its rotation to successively present different portions of the tray at the access opening of the chamber.
9. In a lantern as described, an annular chamber concentric with the base of the lantern, and having an access opening, a tray concentrically located within the chamber, the tray and chamber being rotatable whereby successive portions of the tray will be presented at the access opening of the chamber.
10. In a lantern having a hollow base, having an access opening thereinto, a revolute tray located within the base chamber of the lantern and partitions dividing the tray into a plurality of compartments, said compartments being adapted to be successively presented at the access opening of the base chamber by the revolute adjustment of the tray.

In testimony whereof, I have hereunto set my hand this 19 day of September 1912.

SAMUEL BORLAND.
